DOOR AND FRAME ASSEMBLY

Abe Zitomer, Detroit, Mich., assignor to Feather-Lite Manufacturing Co., division of General Capsule Corp., Detroit, Mich., a corporation of Michigan

Filed Oct. 24, 1963, Ser. No. 319,923

8 Claims. (Cl. 49—193)

This application is a continuation-in-part of my prior copending application Serial No. 276,899, filed April 30, 1963, for "Door and Frame Construction for Combination Door," now abandoned.

This invention relates to door and door frame assemblies of the prehung type and has particular reference to certain new and useful improvements in the construction thereof wherein the hinging is such that the door may be hung on either side when the assembly is being installed. Because of this it is not necessary to make or stock right-and left-hand doors as such, whereby the inventory of doors required to be stocked by the manufacturer and the dealer need be but half of that conventionally required.

A principal object of the invention therefore is to provide a new and improved door and frame assembly for combination doors.

Another object of the invention is to provide a door and frame assembly for combination doors whereby the door when installed may be readily hung on either side and whereby the door and frame may be sold as a package ready for installation by a home owner.

Other and further objects of the invention will be apparent from the following description and claims and may be understood by reference to the accompanying drawings, of which there are three sheets, which by way of illustration show preferred embodiments of the invention and what I now consider to be the best mode of applying the principles thereof. Other embodiments of the invention may be used without departing from the scope of the present invention as set forth in the appended claims.

In the drawings:

FIG. 1 is a perspective view of a door and frame construction embodying the invention;

FIG. 2 is a similar view of the construction, showing the door hung from its other side edge;

FIG. 3 is an enlarged fragmentary sectional view taken along the line 3—3 of FIG. 1;

FIG. 4 is a fragmentary vertical sectional view taken along the line 4—4 of FIG. 1;

FIG. 5 is a horizontal sectional view taken along the line 5—5 of FIG. 4;

FIG. 6 is a fragmentary vertical sectional view taken along the line 6—6 of FIG. 1;

FIG. 7 is a fragmentary sectional view taken along the line 7—7 of FIG. 2;

FIG. 8 is an enlarged sectional view of the hinge included in the circle F of FIG. 7;

FIG. 9 is a fragmentary sectional view through the door and door frame and illustrating the manner in which such parts are interlocked to form a shipping package;

FIG. 10 is a view similar to FIG. 1, illustrating a modified form of the invention;

FIG. 11 is an enlarged sectional view taken along the line 11—11 of FIG. 10;

FIG. 12 is a sectional view taken along the line 12—12 of FIG. 11; and

FIGS. 13 and 14 are sectional views illustrating modified forms of frame construction.

As illustrated in FIGS. 1, 2, 3, 6 and 7, the door and door frame assembly in general comprises a U-shaped

2

frame 10 defining the sides and top of a door opening and a door or closure 12, the door frame 10 and door 12 being provided with integral hinge members to provide a hinge 14 for swingingly supporting the door on one edge as shown in FIGS. 1 and 3, and with hinge members on the other edge of the door to form a hinge 16 for swingingly supporting the door on its other edge as shown in FIGS. 2 and 7, whereby the door 12 may be hinged at either edge. The assembly is shipped with the door hinged at one edge. However, when the assembly is installed, the door may be readily hung so that it is hinged at either edge.

The door frame 10 preferably is formed of side frame members 18 and 20 and top frame member 22 which define the sides and top of a door opening. The members 18, 20 and 22 are preferably Z-bars formed by aluminum extrusions, the crossframe member 22 being suitably secured to the upper ends of the side frame members 18 and 20 so as to define a U-shaped frame. The side frame member 18 is provided with an integral vertical rib 24, and the side frame member 20 is provided with an integral vertical rib 26, such ribs 24 and 26 being disposed laterally of the door opening and co-extensive with the height of the side frame members 18 and 20. The ribs 24 and 26 project outwardly of the door opening.

The door for closing the opening is also provided along each vertical side edge with vertical ribs 28 and 30 which are substantially co-extensive with the vertical height of the door. The vertical ribs 28 and 30 project outwardly of the door and are parallel to each other and to the ribs 24 and 26 on the frame members. The interengaged ribs 26 and 30 shown in FIG. 3 cooperate to form the hinge 14, while the ribs 24 and 28 on the other side of the door and door frame cooperate as shown in FIG. 7 to form the hinge 16. However, the ribs 24 and 26 on the door frame members 18 and 20 are spaced apart a greater distance than the ribs 28 and 30 on the door so that when the hinge members on the one edge of the door and the adjacent edge of the frame are operatively assembled to form the hinge 14 as shown in FIG. 3, the rib 28 on the other edge of the door will seat on the door frame 18 inwardly of the rib 24 thereon when the door is closed as shown in FIG. 3.

As shown, the ends of the ribs 24, 26, 28 and 30 are curved in cross section with the door frame ribs 24 and 26 curled about a larger radius and to a substantially greater extent than the door ribs 28 and 30 so that when the ribs 26 and 30 are interengaged to form the hinge 14, the hinge members will interlock in all positions of the door from closed to about 90° open. FIG. 8 shows the ribs 24 and 28 interlocked to provide the hinge 16, and shows that when the door is open to a 90° position the bead 29 forming the edge of the rib 28 will not clear the bead 25 forming the free edge of the rib 24. It will be evident, however, that by opening the door to an open position slightly greater than 90° open, the curled edge of the rib 28 will clear the bead 25 on the curled edge of the rib 24 and permit the disassembly of the hinge 16 by moving the door 12 in a direction across the door opening. From the foregoing it will be evident that the door 12 and the frame 10 are made so that the door 12 may be hung on either of its side edges simply by engaging the ribs 26 and 30 to form the hinge 14, or the ribs 24 and 28 to form the hinge 16.

It will be further evident that the rib on the free edge of the door, such as the rib 28 in FIG. 3, will fit within the adjacent rib 24 on the door frame and seat on the door frame as illustrated in FIG. 3. Since the rib 24 thus overlaps the rib 28, it will shield the same and cooperate

therewith to provide an air seal at the outer edge of the door which will be in addition to the seal provided between the inner face 32 of the door and the sealing strip 34 carried by the flange 35 of the frame member 18. The flange 35 is adapted to seat against the stop 36 of the wooden door frame to which the side frame members 18, 20 and 22 are secured by screws. The cross frame member 22 at the top of the door opening includes a rib 38 which overhangs the upper edge of the door in its closed position, as shown in FIG. 6.

The lower ends of the ribs 28 and 30 are cut off a short distance above the bottom edge of the door, as shown in FIG. 4, and rest upon a nylon bearing member or wear plate 40 carried by a plug 42 which has a shape to fit within the rib 26 on the door frame member 20 whereby the weight of the door is taken by the bearing member 40. Preferably the bearing member 40 is made of nylon so as to provide a surface upon which the lower end of the rib 30 will freely slide. The lower end of the door is provided by an adjustable channel-shaped bar 44 which telescopes over the lower frame member 46 of the door as shown in FIG. 6. The bar 44 carries a gasket 48 which cooperates with the door sill 50 to close the gap between the bottom edge of the door and the sill 50. The bar 44 is adjustable on the frame member 46, and after being adjusted to the desired position is secured by means of one or more screws, such as 52. The bar 44 before being fastened by the screws 52 is adjusted crosswise of the door so as to clear the interlocking ribs which form the hinge on which the door is hung and to overlap the plug 42 and the wear plate 40 on the free side of the door.

Looking at FIG. 8, it will be noted that the rib 28 and the flange 33 ride on the inner surface of the rib 24 and the forward face 35 of the door frame member 18. This arrangement avoids the necessity for close tolerances on the dimensions of the ribs and the beads 25 and 29 and makes it possible to provide a hinge which is relatively free of binding, which might otherwise occur. Since the ribs 28 and 24 and the corresponding ribs on the other side extend substantially the full length of the door opening, the wear and the load on the interengaging hinge surfaces is distributed over a large area. In addition, this type of hinge construction completely eliminates gaps on the hinge side of the door through which insects or air can pass so that the door is effectively sealed to the door frame on its hinged side throughout substantially the entire height thereof. The nesting arrangement of the door frame and door ribs on the free side of the door edge also provides an effective wind and insect seal along the free edge of the door.

In order to make the hinge member on the hinge side of the door ride on the inside surface of the hinged member on the door frame, as illustrated in FIG. 8, and to prevent accidental separation of the hinge members, means are provided which bias the door to its closed position and limit the degree of opening movement thereof. Such means may comprise a spring door closer and check 60 as illustrated in FIG. 3 which is hinged at 62 to a bracket 64 which is adjustably secured on a channel-shaped frame 66 carried by the door. The piston rod 68 of the door closer 60 is pivoted at 70 to a bracket 72 which is mounted on the door stop 36. The door closer 60 biases the door 12 to its closed position and biases the hinge member 28 on the door as shown in FIG. 8 so as to engage the inner surface of the hinge member on the door frame. The door closer or check 60 limits the opening movement of the door to about 90° open so as to prevent the accidental separation of the hinge members.

The door frame construction illustrated is preferably made up of a number of lengths of Z-bar aluminum extrusions which are assembled to form a U-shaped frame. Except for the ribs along the side edges of the door, the door is preferably constructed of hollow aluminum ex-

trusions, and the ribs 28 and 30 preferably are made integrally with the frame members which form the sides of the door. Holes 82 are provided on each side of the door so that a door handle may be readily attached on the appropriate side of the door.

The door and frame are packaged and shipped as a unit with the door hinged onto one side of the frame and held in a closed position in the frame by the use of three protective clamps 80. The clamps are mounted on frame 18 by means of screw 86. As shown in FIG. 9, middle clamp 80 is located so as to cover door handle hole 82. A plastic plug 84 is forced through a hole in the clamp and through hole 82 to additionally secure this clamp. The upper and lower clamps 80 are secured by means of screws 86 alone. The clamps fit closely around the door frame and door member and between ribs 24 and 28 to hold the door against sealing strip 34 and the engaged rib 26 to prevent movement of the door in the frame.

In the modifications illustrated in FIGURES 10 to 14, inclusive, the construction of the door and frame assembly is in many respects the same as that of FIGURES 1 to 8. However, the modifications of FIGURES 10 to 14 include in addition to the construction described in FIGURES 1 to 8 one or more retainers 100 mounted on the frame member 20 and positioned in the path of movement of the hinge member 130 on the door so as to be engaged by the latter when the door is swung to its open position and form a stop. As shown in FIGURES 10, 11 and 12, the retainer comprises a series of angular members formed of a suitable material such, for example, as nylon, each of the members 100 being secured to the frame member 20 by a screw 102. One leg 101 of the member 100 is positioned against the outer surface of the frame 20 adjacent the inner corner thereof and thus serves to reduce the gap or clearance between such part of the frame and the curled-over end 105 of the hinge member 126 which is integral with the frame 20. In this position the member 100 is engageable with the hinge member 130 as illustrated in FIGURE 11 so as to form a stop for limiting the opening movement of the door and at the same time preventing separation of the hinge members 126 and 130. The retainer 100 also functions as a bearing plate upon which the edge of the door hinge member freely slides and rides. The retainer 100 also compensates to some extent for variations in the size and shape of the hinge members 126 and 130. The hinge members and the parts integral therewith are preferably formed as aluminum extrusions, and it is not uncommon to encounter a certain amount of warpage and distortion in parts so formed. By using the retainers 100, it is possible to form the hinge members somewhat less critically and at the same time provide a hinge which can be easily assembled and disassembled and which will operate freely without binding. It will be evident that in the case of the construction illustrated in FIGURES 10, 11 and 12 the retainer 100 is installed after the hinge members have been assembled. The retainers are required, of course, only on the hinge side of the door opening. In lieu of using the nylon retainer 100, I may employ spring retainers such as the retainer 200 illustrated in FIGURE 14 or the retainer 300 illustrated in FIGURE 13. The spring retainers 200 and 300 preferably are formed of stainless steel. The retainer 200 includes an exposed spring arm 202 which cooperates with the hinge member 130 so as to be engaged by the latter and form a resilient stop therefor. In the retainer 300 illustrated in FIGURE 13, the end 302 is folded inwardly so as to react on the frame member 20. The retainers 200 and 300 function similarly and, when the door is only partly open, will exert a spring action tending to bias the door to its closed position. I contemplate that in assemblies constructed in accordance with FIGURES 10 to 14 a door closure and check like that il-

lustrated in FIGURE 3 will be employed where it is intended that the door be normally closed.

While I have illustrated and described preferred embodiments of my invention, it is understood that these are capable of modification and I therefore do not wish to be limited to the precise details set forth but desire to avail myself of such changes and alterations as fall within the purview of the following claims.

I claim:

1. A door and frame assembly comprising a frame defining the sides of a door opening and including vertical side frame members each having a vertical rib projecting outwardly of said door opening, a door for closing said opening, each vertical side edge of said door having an integral vertical rib projecting outwardly of said door, said vertical ribs on said door frame being parallel to said ribs on said door, each of said ribs on said door forming a hinge member and each of the ribs on said door frame forming a hinge member so that the hinge member on each side of said door is operable when operatively assembled with the adjacent hinge member on said door frame to provide a mounting for said door on said frame, said ribs on said door frame being spaced apart a greater distance than said ribs on said door, said hinge members when engaged to form a hinge interlocking in all positions of the door from closed to open position thereof, said door being provided with handle and lock mounting holes adjacent each side edge thereof.

2. A door and frame assembly comprising a U-shaped frame defining the sides of a door opening and including vertical side frame members each having an integral vertical rib disposed laterally of said door opening and projecting outwardly of said door opening, a door for closing said opening, each vertical side edge of said door having an integral vertical rib projecting outwardly of said door, said vertical ribs on said door frame being parallel to said ribs on said door, each of said ribs on said door forming a hinge member and each of the ribs on said door frame forming a hinge member so that the hinge member on each side of said door is operable when operatively assembled with the adjacent hinge member on said door frame to provide a hinge mounting for said door on said frame, said ribs on said door frame being spaced apart a greater distance than said ribs on said door, means forming part of the hinge mounting of the door frame and cooperable with the hinge member on the door for supporting the latter for hinging movement between its open and closed positions, said hinge members when engaged to form a hinge interlocking in all positions of the door from closed to open position.

3. A door and frame assembly according to claim 2 including a retainer on the door frame positioned to cooperate with the hinge member on the door to prevent separation thereof from the hinge member on the door frame.

4. A door and frame assembly comprising a U-shaped frame defining the sides of a door opening and including vertical side frame members each having a vertical rib disposed laterally of said door opening and projecting outwardly of said door opening, a door for closing said opening, each vertical side edge of said door having a vertical rib projecting outwardly of said door, said vertical ribs on said door frame being parallel to said ribs on said door, each of said ribs on said door forming a hinge member and each of the ribs on said door frame forming a hinge member so that the hinge member on each side of said door is operable when operatively assembled with the adjacent hinge member on said door frame to provide a hinge mounting for said door on said frame, said ribs on said door frame being spaced apart a greater distance than said ribs on said door so that when the hinge member on one edge of the door is operatively assembled with the adjacent hinge member on the door frame so as to thereby hingedly mount the door

on said frame, the rib on the other edge of said door when the latter is closed will seat on the door frame inwardly of the other rib thereon, a bearing member mounted on the door frame rib forming part of the hinge mounting of the door so as to support the latter for hinging movement between its open and closed positions, said hinge members when engaged to form a hinge interlocking in all positions of the door from closed to open position.

5. A door and frame assembly comprising a U-shaped frame defining the sides and top of a door opening and including vertical side frame members each having a vertical rib disposed laterally of said door opening and co-extensive with the height thereof and projecting outwardly of said door opening, a door for closing said opening, each vertical side edge of said door having a vertical rib substantially coextensive with the height of said door, said vertical ribs on said door projecting outwardly of said door, said vertical ribs on said door frame being parallel to said ribs on said door, each of said ribs on said door forming a hinge member and each of the ribs on said door frame forming a hinge member so that the hinge member on each side of said door is operable when operatively assembled with the adjacent hinge member on said door frame to provide a hinge mounting for said door on said frame, said ribs on said door frame being spaced apart a greater distance than said ribs on said door so that when the hinge member on one edge of the door is operatively assembled with the adjacent hinge member on the door frame so as to thereby hingedly mount the door on said frame, the rib on the other edge of said door when the latter is closed will seat on the door frame inwardly of the other rib thereon, a bearing member mounted on the door frame rib forming part of the hinge mounting of the door so as to underlie the cooperable hinge member on the door for supporting the latter for hinging movement between its open and closed positions, the ends of said ribs being curved in cross section with the door frame rib ends curled about a larger radius and to a substantially greater extent than the door ribs so when said ribs are engaged to form a hinge, the hinge member will interlock in all positions of the door from closed to about 90° open but may be separated beyond such open position, and means limiting the degree of opening of said door so as to prevent accidental separation of the hinge members.

6. A door and frame assembly according to claim 5 wherein said limiting means comprises a door closer which biases said door to its closed position.

7. A door and frame assembly according to claim 5 wherein said limiting means comprises a retainer on one of said hinge members which is positioned in the path of movement of the other hinge member so as to be engaged by the latter and form a stop therefor.

8. A door and frame assembly according to claim 5 wherein said limiting means comprises a retainer spring on one of said hinge members which is positioned in the path of movement of the other hinge member so as to be engaged by the latter and form a resilient stop therefor.
